UNITED STATES PATENT OFFICE

JOHN BLAIN HUNT, OF PENYLAN, CARDIFF, WALES

BOAT LOWERING GEAR

Application filed April 13, 1932, Serial No. 604,924, and in Great Britain April 17, 1931.

This invention relates to boat lowering gear of the kind comprising a pair of davits which serve to support a boat for example a lifeboat, in the inboard position and are movable into the outboard position to permit the boat to be launched either manually or by winch or other mechanism when required.

The chief object of the invention is to construct boat lowering gear which may be used for launching lifeboats from ships or other vessels irrespective of any list which may be assumed by the vessel due for example to accident, and further to provide boat lowering gear which in the event of the davit failing to function as a result of damage or other cause will enable the lifeboat to be launched whether the davits are in the inboard or outboard position.

According to the invention the davits are pivotally supported at their bases upon the deck of the vessel at points spaced from the side thereof in such a manner as to be capable of swinging laterally from an inboard to an outboard position each davit being slidably connected to one end of a strut, the other end of which is pivotally connected to the deck of the vessel at a point disposed above the side thereof, stops being provided on each davit for engaging the strut or a part associated therewith for limiting sliding movement between said strut and davit. The davits are preferably constructed of H girder section, are curved outwardly and have mounted at the free ends thereof a device known as a fair lead over which are passed falls for supporting the boat, the falls being connected to winch or other mechanism by means of which the boat may be raised or lowered when desired. The strut is also of metal of H girder section and in the inboard position of the davit is disposed at an angle of approximately 45° to the deck of the vessel, and when the davit is moved to the outboard position the strut assumes a position in line with the side of the vessel. The free end of each strut is provided with a pair of plates which extend on each side of the corresponding davit and carry rollers between which the davit is positioned and which bear against the davit and permit the same to

move easily from the inboard to the outboard position. Upper and lower stops are secured to each davit to limit the movement of the strut relatively to the davit and thereby determine the inboard and outboard positions of the davit.

The struts are each provided with chocks which support the boat in the inboard position, the said chocks being movable to permit the boat to ride down the diagonally disposed struts into an outboard position, the weight of the boat in its outward movement swinging the davits on their pivots and bringing them into the outboard position, whereby the boat is swung clear of the vessel and may be lowered through the medium of the usual winch mechanism and launched.

The invention is particularly applicable to lifeboats fitted with skates such for example as described in the specification of English Patent No. 329,274. Where skates are employed the struts are connected by means of a horizontally disposed rest bar disposed intermediate the ends thereof which serves to support a pair of slides or runways arranged between the davits and pivotally connected to the deck in alignment with the pivotal points of the struts and allowed to bear upon the rest bar so that when the davits assume an outboard position the slides move with the struts and assume a position of alignment with the side of the vessel. The slides or runways form continuations of slides or runways secured to the side of the vessel and down which the lifeboat slides through the medium of the skates thereon until sea level is reached.

In order that the said invention may be clearly understood and readily carried into effect reference is directed to the accompanying drawings wherein:—

Figure 1 is an end elevation of boat lowering gear constructed in accordance with the invention and showing in full lines the inboard position of the gear and in dot and dash lines the outboard position thereof.

Figure 2 is a front elevation of the gear illustrated in Figure 1 with the lifeboat disposed in the inboard position.

Figure 3 is a plan partly in section on the line 3—3 in Figure 1.

The davits 1 and 2 are pivotally connected with the deck 3 of the vessel by means of hinge pins 4 and 5 respectively. The davits are curved in an outboard direction and furnished at their free ends with fair leads 6—6 over which falls 7 extend and support a boat 8 through the medium of the sheave blocks 9, the boat being raised or lowered when required through the medium of winch or other mechanism (not shown).

Each davit is slidably connected to one end of the corresponding strut 10, the other end of which is pivotally connected to the deck of the vessel in such a manner that the davit may automatically move from the inboard position indicated in full lines in Figure 1 to the outboard position indicated in dot and dash lines when the boat 8 is launched, the movement of each davit from the inboard to the outboard position being controlled by means of stops 11 and 12 secured to each davit to engage the strut. Each of the struts 10 has secured thereto a pair of plates 13 and 14 which embrace the respective davit and carry rollers 15 and 16 which serve to guide the davit 1 in its lateral movement, the said plates abutting against the stops 11 and 12 respectively in the outboard and inboard positions of the said davits, and thus determine the position of the davits relative to the deck of the vessel. The arrangement is such that in the inboard position of the davits the struts 10 assume an angle of approximately 45° with respect to the level of the deck and in the outboard position of the davits are substantially in line with the side of the vessel so that the weight of the boat and the stresses set up during launching are taken by the side of the vessel.

The struts 10 are fitted with chocks 17 pivotally connected to the struts at 18 and each held in operative position by means of a removable pin 19 entering the associated strut so that in the inboard position of the davits the boat is supported in its normal out-of-use position. Upon removal of the pins 19 the chocks will fall by gravity and thereby release the lifeboat, whereupon operation of the winch mechanism to lower the lifeboat will allow the same to descend until the action of its weight is sufficient to pull the davits 1 and 2 automatically from the inboard to the outboard position, so that the boat is swung clear of the side of the vessel and may be lowered to sea level and launched in the usual manner.

Where the invention is applied to lifeboats fitted with skates such for example as described in the said English specification No. 329,274, the skates are used in conjunction with the horizontally disposed rest bar 20 which is connected to the struts 10 inter-

mediate the ends thereof and serves to support a pair of slides or runways 21 and 22 which are pivotally connected to the deck at their lower ends through the medium of the pivot pins 23 and 24 in alignment with the pivotal points of the struts 10, so that when the davits assume the outboard position the slides also move forward with the struts and assume a position in alignment with the side of the vessel.

The slides or runways 21 and 22 form a continuation of slides or runways secured to the side of the vessel in accordance with the said English specification No. 329,274 so that upon release of the boat 8 the skates will serve to guide the boat down the runways 21 and 22 and thereafter along the runways secured to the side of the vessel until sea level is reached, this arrangement being particularly applicable where the starboard boats have to be launched from a vessel having a list to port, or vice versa.

The position of the base of the davit and the point where the struts 10 are pivoted to the deck of the vessel is so determined as to allow of the inboard stowage of the boat and permit the boat to be lowered clear of the ship's side when the davits are in the outboard position and at the same time give the required angle to the struts 10 relative to the level of the deck of the vessel.

When it is required to operate the davit the chocks supporting the boat are released, whereupon the boat is ready for launching through the medium of the winch mechanism. As the boat is lowered the inclined struts 10 leave the lower stops 12 and slide along the davits 1 and 2 until they come into contact with the upper stops 11, whereupon the boat is brought into the outboard position and is ready to be lowered clear of the ship's side. Where the vessel has assumed a list the boats on the higher side thereof slide down the runways 21 and 22 and the runways secured to the side of the vessel and the davits automatically assume the outboard position immediately the weight of the boat is sufficient to draw the davits into the forward position.

Should the davits due to damage remain in the inboard position the release of the chocks still enables the boats to be lowered. Similarly in the case of lowering boats on the low side of a listed vessel the davits remain fixed in their inboard position thus facilitating the embarkation of passengers with the maximum of safety and the lifeboat may be thereafter lowered close into the vessel.

In order to check the possibility of shock when the inclined strut assumes the outboard position, shock absorbers may be employed, further a suitable outboard stop can be applied to maintain the strut in the outboard position on the high side of a vessel having extreme list.

The use of gear according to this invention enables a lifeboat to be ready for direct launching immediately at all times irrespective of the conditions of trim of the vessel, 5 by the simple operation of releasing the chocks so that the boat is lowered and the davits operated simultaneously; further the skates when attached to the lifeboat as a means of dealing with list only require davits 10 modified to give entrance for the lifeboat plus the depth of the skate and do not require an abnormal outboard span in order to launch boats from a vessel having an abnormal degree of list.

15 What I claim and desire to secure by Letters Patent of the United States is:—

1. In boat lowering gear the combination of a pair of davits each pivotally supported at its base upon the deck of the vessel at a 20 point spaced from the side thereof so as to be swingable laterally from an inboard to an outboard position, a pair of struts each of which is pivotally connected to the deck of the vessel at a point disposed above the side 25 thereof, a slideable connection between each strut and one of said davits and means for limiting sliding movement between each davit and its associated strut.

2. Boat lowering gear as in claim 1, where- 30 in each strut is slideably connected to the re- spective davit by means of a pair of plates which embrace the davit and support rollers which bear upon the davit.

3. Boat lowering gear as in claim 1, where- 35 in the struts are supported by a horizontally disposed rest bar and operate in conjunction with a pair of runways for the purpose speci- fied.

4. Boat lowering gear as in claim 1, where- 40 in the struts are each provided with chocks which support the boat in the inboard posi- tion the said chocks being movable to release the boat.

JOHN BLAIN HUNT.
